UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,381, dated October 31, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The face of the design is irregularly traversed by angular stems bearing variously shaped gems and angular leaf forms. These are more closely massed along the outer and inner portions of the design, where they overlie a different ground. The general effect produced is that of a border consisting of three bands, the inner one of which is the narrowest and the outer one the widest, the middle band

presenting the most open appearance. The width of the inner band is one of the peculiarities of the design, it being wider in comparison with the middle band than is usually the case with designs for borders. The outer and inner bands differ from the middle band in having a more symmetrical arrangement of gems and leaf forms with less conspicuous stem-connections; but the arrangement in the outer band is different from the arrangement in the inner band, as fully appears from the accompanying photograph.

I claim—

The design for carpets, consisting of the border design, substantially as shown and described.

WINTHROP L. JACOBS.
